UNITED STATES PATENT OFFICE.

JOSEFA O'NEILL DE CARACENA, OF NEW YORK, N. Y.

DRESS-WAIST.

SPECIFICATION forming part of Letters Patent No. 408,594, dated August 6, 1889.

Application filed January 19, 1889. Serial No. 296,803. (No model.)

To all whom it may concern:

Be it known that I, JOSEFA O'NEILL DE CARACENA, a resident of the city, county, and State of New York, have invented a new and 5 useful Improved Waist; and I do hereby declare that the following is a full and exact description thereof, reference being had to the accompanying drawings, and to the letters of reference marked thereon, making a part of 10 this specification.

My invention relates to the waists of ladies' outer garments—such as dresses, sacks, jackets, &c.—and has for its object to greatly reduce the amount of material, time, and labor 15 required in making them, and consequently the cost thereof.

In making the waists of ladies' garments close-fitting in the front and back it has heretofore been customary to cut out twelve distinct pieces of material of suitable forms—viz., two front pieces, two back pieces, four under-arm gores, and two pieces for each sleeve, requiring for their union nineteen connecting seams—viz., two side seams, one back 25 or front center seam, two shoulder-seams, four under-arm gore-seams, four bust-dart seams, two connection seams of sleeves to body, and four sleeve-seams.

By my invention the waist is made complete 30 with but seven seams, saving about sixty per cent. of time and labor in sewing and from thirty to forty per cent. of material in cutting out.

It consists of a dress-waist each half of 35 which is formed solely of a front and back of one piece and each having substantially the special configuration hereinafter particularly described and claimed.

In the accompanying drawings, Figure 1 is 40 a view in perspective of the front and one side of a lady's basque made from my improved single pattern, one of the sleeves being removed; Fig. 2, a similar view of the same from the opposite side. Fig. 3 is a plan 45 of the two pieces of which the waist is constructed when opened out, illustrating the form thereof; and Fig. 4, a plan view of the single piece of which one of the sleeves is formed.

50 A A', Fig. 3, represent the two pieces of material which, when united, as in Figs. 1 and 2, form the waist, and B, Fig. 4, represents the

single piece of material for each sleeve, which is to be united to the waist in the customary manner, as shown in Figs. 1 and 2. The two 55 waist-pieces are precisely alike in their dimensions and outlines, and hence where the cloth is reversible may both be cut at the same time from superimposed pieces of the fabric, thereby saving time, labor, and mate- 60 rial in the operation.

The pattern for each piece is formed in two lengths *a* and *b*, diverging from a central point at an angle more or less obtuse, and a line *c d*, bisecting said angle, determines the 65 center of the band to connect the front and back of the waist over each shoulder. In drawing said pattern this shoulder-line *c d* is first drawn, and a line *e e'* is drawn to intersect it at a right angle. The terminal point at *c* of 70 the line *c d* is determined by the distance between the neck and the outer end of the shoulder-blade in the measurement of the person to be fitted. The points *e* and *e'*, terminating the line *e e'*, are determined by the intersection 75 with said line of the arcs *e k e' k'*, described from the point *c* as a center, each with a radius equal to the measure of the person to be fitted taken in front from a point, as *c*, at the intersection of the neck and middle of 80 the shoulder down to the waist over the bust, and which I shall designate as the "bust-measure." A semicircle, whose arc is equal to one-half the measured circumference of the neck, is then drawn from a point *f* on an extension of the line *c d* so as to intersect the point *c*. From said center point *f*, or from a point a little beyond it in line with *c d*, lines are drawn to each end of the line *e e'*. These lines, intersecting at *g g'* the arc described 85 from the point *f*, determine the neck-line *g c g'*. A second semicircle *i d i'* is described from a center point *h*, in line with *c d* beyond the point *d*, with a radius equal to that of the measured diameter of the arm-hole required 90 in the garment, so that the described arc shall intersect the line *c d* at or a little within the said point *d*. The distance of the point *k* from the point *e* on the arc *e i* in the front length *a* of the waist-piece is made equal to 95 three-tenths of the bust-measure, and the distance of the point *k'* from the point *e'* on the corresponding arc *e' i'* for the back length *b* is made equal to two-tenths of the bust-meas- 100

ure. The point k is connected with the proximate end i of the arms-eye semicircle $i d i'$ on the front length a of the waist-piece by a line $k i$, curving slightly outward from a straight course to form a slight outward bend as it approaches the terminal point i of the arms-eye curve, and the point k' on the back length is connected with the point i' at the proximate end of said curve $i d i'$ by a line $k' i'$, curving very slightly inward as it leaves the point k' and thence extending directly to the point i' .

The end g of the neck-curve $g c g'$ is connected with the waist-line at e on the front length a by an outwardly-curved line $g e$, whose measured length equals that of the line $c e$, while the opposite end g' of the neck-curve is connected with the waist-line at e' on the back length b by a straight line $g' e'$.

The line $e e'$ is extended at each end to a distance equal to the length desired in the basque below the waist-line, with a slight outward curve $e l$ at the front and a counterpart slight inward curve $e' l'$ at the back, and the lines $i k$ and $i' k'$ are correspondingly extended to m and m' , but with a sharp outward bend, determined by the fullness desired in the lower part or skirt of the basque, the points $e m$ and $i m$ being connected by outwardly-curved lines $l m l' m'$, as shown in Fig. 3 of the drawings.

In cutting out the pattern a suitable margin is allowed for the seams, in the usual manner.

The two waist-pieces $a b$, cut out from the pattern formed by the outer lines connecting, as described, the several points $c g e l m k i$ and $i' k' m' l' e' g' c'$, as shown in Fig. 3, are united to form the waist or basque by simply

stitching together the corresponding edges $g e l$ of the two pieces, if the waist is to open at the back, or the edges $g' e' l'$ if it is to open

at the front, and by stitching together the opposite edges $i k m$ and $i' k' m'$ of each piece to close the arm-holes and form the side or under-arm seams.

The sleeves, to be united in the customary manner to the waist thus formed, may each be made of a single piece B, cut for a close-fitting sleeve in the general form shown in Fig. 4—viz., with the opposite edges (which are of a length equal to the length of the sleeve) cut each with a corresponding inward curve $n o n' o'$ to about midway the length of the sleeve, and thence upon the one side in nearly a straight line $o p$, and upon the other with an outward curve $o' p'$ to the end p' of the sleeve, said opposite edges $n p$ and $n' p'$ being stitched together to complete the sleeve.

I claim as my invention—

A dress-waist each half of which is formed solely of a front and back of one piece, the two pieces having the same configuration and each consisting of two lengths a and b , of varying widths, diverging at an angle more or less obtuse from opposite neck and arm curves $g c g'$ and $i d i'$, the wider front length a having outwardly-curved side lines $g e$ and $i k$, converging slightly to the waist-line, and the narrower or back length b having straight side lines $g' e'$ and $i' k'$, converging slightly to the waist-line, and both widening with outwardly-curved lines beyond the waist-line, substantially in the manner and for the purpose herein set forth.

In testimony whereof I have signed my name to this specification in the presence of two subscribing witnesses.

JOSEFA O'NEILL DE CARACENA.
